RAIL BRACE

James H. Asselin, Winnetka, Ill.

Application April 28, 1947, Serial No. 744,285

2 Claims. (Cl. 238—292)

1

This invention relates to rail braces for railway track, and this application is a continuation-in-part of application Serial No. 593,979, filed May 16, 1945, now Patent No. 2,426,137, dated August 19, 1947.

It is a well-known phenomena that as a train approaches a section of track, it sets up in that track a vertical up-and-down "wave" or "floating" action of the rail. Such rail "wave" motion is inherent in train movement over track and apparently cannot be prevented, even if this would be desirable. There are in fact many reasons which point to the fact that such flexibility in track is both necessary and important. Be that as it may, such "wave" motion has rendered it impossible to provide a rail brace of the bolted type in which the securing bolt or bolts will not loosen in time as the result of the vibratory forces set up by such "wave" motion of the rail.

The present invention is directed to a rail brace which is a combination of the bolted and non-bolted types, that is, which is provided with one or more bolts which are adapted to secure the brace member to the tie plate and also with other means for securing the brace in place which cooperate with the bolt securing means and are also capable of acting independently.

The invention accepts the fact that securing bolts will in time become loose, and that if not tightened from time to time, the effectiveness of the rail brace will be diminished or completely lost, if they be the only means provided. Consequently, the invention provides, besides the bolt-securing means, another fastening arrangement, which not only cooperates with the bolt-securing means but also effectively operates to maintain the rail brace in fully operative bracing position even after the securing bolts referred to have become loosened, or even if such bolts should by accident become broken. Such other fastening means as the invention provides are of a special nature and in the preferred form are comprised of a block secured to the tie plate, and a wedge disposed between the block and the brace member, the connection between the wedge and the brace member being in the form of a cylinder and socket joint, and the connection between the wedge and the block being such as to permit a limited pivoting or hinging movement of the wedge.

2

Thus, accepting the fact that the securing bolt or bolts comprising one of the fastening means for the brace member will become loosened by vibration, the brace member will still be maintained in rail-bracing position as the result of the structure referred to above. Moreover, such structure comprises means for urging the brace member into rail-bracing position before the bolts are initially tightened, and then cooperates with them in securing the brace in bracing position before the bolts become loosened by vibration.

It is to be understood that, in fact, both fastening means are equally important to the invention. Both means play an essential and vital role in cooperating to provide an effective and satisfactory rail brace.

It is a principal object of the invention to provide such a rail brace.

20 Attention is called to the fact that with such structure, and after the securing bolts have become loosened, the other securing means is so constructed that the "wave" motion of the rail is permitted to a limited degree, but it is controlled above the tie plates, and only a minor portion is permitted to transcend through the tie plates into the ties or through the ties to the ballast. By so controlling and limiting the effect of this motion, the wear will be between 25 the rail and tie plate, or between steel and steel. Thus wear on ties and loosening of ballast is greatly reduced. This is made possible by reason of the cylinder and socket connection between the brace member and the wedge, and because 30 of the limited pivoting or hinging action permitted between the wedge and the block. Such structure provides the flexibility necessary to accommodate the "wave" or "floating" movement of the rail as a train passes thereover. It is an 35 important object of the invention to provide a rail brace having such characteristics.

Still further, adjustable rail braces now known and which use ratchet toothed wedges or the like, are highly susceptible to wear, rust and 40 corrosion due to weather conditions and salt brine. Many of them, moreover, are complicated by having too many parts, thus materially increasing the original cost, the cost of installation, and the cost of maintaining proper adjustment. These difficulties and disadvantages have 45 been overcome to a great extent by the present

invention and it is a primary object of the invention to accomplish these aims.

The invention also makes use of a member which is rigid with the tie plate and extends upwardly therefrom and over which the brace member is disposed. This member is adapted to perform a triple function. It prevents the brace member from moving longitudinally of the rail. It serves as an abutment for the rail preventing lateral movement thereof, and it also serves as a means for anchoring the securing bolt or bolts in such a manner that they may be inserted and removed without the necessity of passing them upwardly through a hole in the tie plate. It is a further object of the invention to provide a rail brace having a structure and with such advantages.

A further object of the invention resides in providing a rail brace which may be used on switch rails, in turnouts, spring frogs, guard rails, other curved rail in track and on tangent track. Other uses will suggest themselves to those skilled in the art.

Records show that a large percentage of railroad accidents are the result of too wide track gauge. The gauge of track is frequently maintained by gauge rods which are connected to the base of one rail and with the base of the opposite rail. These are electrically insulated when in a signal section area. Gauge rods have several defects. The insulation fouls, especially in wet weather, thus short circuiting the signal system, but a more important defect is that the gauge of the bases only of the rails is maintained without assuring the gauge of the tops of the rails. The rail tops tip outwardly thus throwing the rails out of gauge. Where, as in curves, frogs, guard rails and switch rails, the track is subjected to abnormal thrusts, the gauge of the rails thus frequently becomes too wide. In curves it has been found that the outer end of the base plate actually cuts into the tie one-half (1/2) inch by side thrust of the rail top, thus widening the gauge one (1) inch. The present invention applied at these sections of track will avoid these disadvantages of gauge rods and will prevent too wide gauge.

The invention also has for an object the provision of a rail brace which engages the rail beneath the head of the rail and also on the upper surface of the base of the rail, the base member being disposed to provide an excellent bearing pressure against the rail at both points. This constant brace pressure maintains canted rails in alignment with the bevel tread wheels, and has the additional advantage of obtaining greater wear of the rails.

These and other objects and advantages of the invention will become more apparent from the following description and claims when read in conjunction with the accompanying drawings in which:

Fig. 1 is a side elevation of one form of the invention, the rail being shown in section;

Fig. 2 is a top plan view of the same;

Fig. 3 is a vertical section taken on the line 3—3 of Fig. 2;

Fig. 4 is a horizontal section taken on the line 4—4 of Fig. 1;

Fig. 5 is an exploded view of the parts;

Fig. 6 is a side elevation of a modified form of the invention;

Fig. 7 is a top plan view of the modification illustrated in Fig. 6;

Fig. 8 is a vertical section through another modified form of the invention;

Fig. 9 is a horizontal section taken on the line 9—9 of Fig. 8;

Fig. 10 is a top plan view of the modification shown in Figs. 8 and 9;

Fig. 11 is a top plan view of a tie plate showing another manner of anchoring a securing bolt, and

Fig. 12 is a vertical sectional view thereof on the line 12—12 of Fig. 11.

Referring first to the embodiment of the invention illustrated on Figs. 1—5 inclusive, the numeral 10 indicates a railroad tie on which is disposed a rectangular metal base or tie plate 11. The upper surface of the tie plate 11 is provided with a transverse shallow cut-out or depression 12. The depression results in two shoulders 13 and 14, the former acting as a transverse rail abutment, and the other 14 acts as an abutment for a block 15 which is secured to the tie plate 11 by means of welding or the like 16.

The rail 17 is disposed with one (inner) edge of the base in engagement with the shoulder 13 and the other edge in engagement with the wall 18 of a positioning member 19 which is welded as at 20 or otherwise secured to the tie plate 11 so as to be rigid therewith. The rail 17 may be secured to the tie 10 by means of spikes 21 which are driven into the tie 10 through openings 22 in the tie plate 11 until the heads of the spikes engage the base flanges of the rail. The tie plate 11 is also provided with openings 23 through which additional spikes or screws (not shown) may be driven into the tie to secure the tie plate 11 to the tie.

The tie plate 11, intermediate its ends, is provided, as stated, with the member 19 which is rigid with the tie plate and extends upwardly from the upper surface of the depression 12. The upstanding vertical wall 18 of the member 19 is a parallel with the shoulder 13 and is so disposed as to provide as abutment for the edge of the base of the rail 17 opposite that engaged by the shoulder 13, and thus prevents the rail from moving laterally. The member 19 has an upper tapered surface 24 which rounds into a forward wall 9 which is at an angle with respect to the wall 18. As indicated, the upper surface 24 of the positioning member 19 is tapered. In fact, it is tapered or slopes downwardly in two directions, first from the upper edge of the vertical wall 18 toward the wall 9, and also slightly from the left to right in Fig. 5.

The positioning member 19 is provided with a rectangular cut-out 25 the side walls of which are substantially at right angles to the wall 9, said cut-out being adapted to receive the head 26 of a securing bolt 27 (see Figs. 3 and 4). The rectangular cut-out 25 communicates with a U-shaped cut-out 28 to receive the shank 29 of the securing bolt 27. An opening 7 in the base of wall 18 communicates with the cut-out 25 to prevent the accumulation of dirt in the cut-out. It will be noted from Fig. 4 that the securing bolt 27 when inserted in place has its head 26 disposed with its edges in angular, non-parallel relationship to the wall 18 and consequently also to the rail 17.

The positioning member 19 preferably may be welded as at 20 to the upper surface of the tie plate 11 all around the edges of the member 19 except along the base of the wall 18 and around the edges of the rectangular cut-out 25. To add strength to the member 19 and also to increase the length of the welding surface, the member is provided with two lateral wings 30 and 31 which in effect are buttressing elements and the outer

surfaces of which are curved into the plane of the upper surface 24 of the positioning member 19. These elements also perform another very important function which will be referred to later on. As indicated, the upper surface 24 of the positioning member 19 is tapered. In fact, it is tapered or slopes downwardly in two directions, first from the upper edge of the vertical wall 18 toward the wall 9, and also slightly from the left to right in Fig. 5.

The base or tie plate 11, near its outer end, as indicated, is provided with the rectangular block 15 disposed transversely thereof. The block 15 may be integrally formed with the tie plate, or may, as shown, be welded thereto as at 16. The inner surface of the block 15 and the rail engaging surface of the shoulder 13 are parallel. For purposes of the invention, as will be more clearly apparent hereinafter, the inner surface of the block 15 is cut with a groove 32 which extends from one end of the block to the other, and which preferably in section has the form of a truncated triangle.

The brace member proper is indicated by the reference numeral 33. This is an irregularly shaped member having a solid wedge engaging portion 34 adapted to rest on the upper surface of the depression 12 of the tie plate 11. The wedge engaging surface 35 of the brace member 33 as will be noted in the drawings is substantially semi-cylindrical in contour and is disposed on a non-parallel angle to the block 15 and also to the rail. The semi-cylindrical surface 35 is spaced from the block 15 so that a wedge may be inserted between the two as will be hereinafter described. From the semi-cylindrical solid portion 34 the brace member 33 extends to the rail, the upper surface 36 of the brace member being first horizontally flat and then sloping upwardly to engage the under surface of the head of the rail 17. Two side walls 37 and 38 connect with the wedge engaging portion 34 and with the upper surface 36. The lower edges of these side walls 37 and 38 engage the upper surface of the base of the rail 17. The web of the rail 17 is not engaged by the brace member.

As will be apparent from Fig. 4, the semi-cylindrical solid portion 34 of the brace member 33 has an inner wall 8 which is in a plane parallel to the longitudinal axis of the semi-cylindrical solid portion 34 of the brace member and also parallel to the wall 9 of the positioning member 19. From Fig. 3 it will be noted that the upper portion of the wall 8 curves toward the rail and merges with under surface of the top portion of the brace member.

The upper surface 36 of the brace member 33 is provided with three holes 39, 40, 41. In the embodiment of Figs. 1-5, the central hole 40 is adapted to have the securing bolt 27 passed therethrough when the device is assembled.

Attention is now directed to the wedge member 42. It will be seen from the drawings that this wedge member 42 is a block which is generally wedge-shaped in form and which is longer than the block 15. On one side the wedge 42 has a laterally extending tongue 43 which in section is in the shape of a truncated triangle and is complementary to the shape of the groove 32 in the block 15 but has a cross-sectional area slightly less than the cross-sectional area of the groove 32.

The brace engaging surface 44 of the wedge 42 is of concave, semi-cylindrical form and is

substantially complementary to that of the semi-cylindrical surface 35 of the brace member 33.

The wedge 42 is adapted to be inserted between the block 15 and the brace member 33 horizontally on the tie plate 11, and in a direction longitudinally of the rail. The wedge is usually pounded into place with a sledge hammer or the like, and it will be seen that as the wedge is inserted, the brace member 33 will be forced inwardly so as to engage the rail 17 under the rail head and also along the upper surface of the base of the rail, as shown in Figs. 1 and 3. After the wedge has been thus inserted it may be locked in position by means of a cotter pin 45 which is adapted to be inserted in one of the series of holes 46 in the end of the tongue 43 of the wedge 42 as shown in Fig. 2.

It will of course be understood, that during the assembly, and before the wedge is inserted, the securing bolt 27 is first inserted in the positioning member 19 with its head 26 in the rectangular cut-out 25 so that the brace member 33 may be positioned over the positioning member 19 with the shank of the securing bolt 27 extending upwardly through the hole 40 in the upper surface of the brace member.

The assembly of the device is completed by disposing a plate 47 (provided with a hole 48 for the passage of the bolt 27) on the upper surface 36 of the brace member; disposing a washer 49 on the bolt; and capping the bolt with a cap-nut 50 which is tightly screwed in place.

It will be seen, particularly in Fig. 4, that the wings 30 and 31 of the positioning member 19, engage the side walls 37 and 38 of the brace member 19 when the latter is disposed in operative position. Consequently, the member 19 prevents the brace member 33 from moving longitudinally of the rail as it has a normal tendency to do, particularly when the wedge is being inserted. It will also be noted that the wings 30 and 31 are curved from the vertical into the plane of the upper surface of the positioning member 19, thus facilitating the placement of the brace member 33 over the positioning member.

The positioning member 19 thus performs three valuable functions. First, it provides an abutment for the rail. Secondly, it provides means whereby the securing bolt 27 may be inserted and anchored after the tie or base plate has been disposed in place, and, finally, the member 19 performs the very valuable function of positioning the brace member and insuring the brace member against movement longitudinally of the rail at all times and particularly when the wedge is being driven into place.

It will now be appreciated that the elements described all cooperate to provide a satisfactory rail brace, and that upon use and as the securing bolt 27 becomes loose, as it will in time, the brace member 33 nevertheless remains in bracing position and continues to brace the rail in proper position.

A modified form of the invention is illustrated in Figs. 6 and 7 inclusive. In this modification, the structure differs in that the securing bolt is not employed. The brace member 51 is held in position by the member 52 and by the wedge 53. Since no bolts are employed, the upper surface 54 of the brace member 51 need not be provided with holes as in the brace member 33 of the embodiment of Figs. 1-5.

Another modified form of the invention is illustrated in Figs. 8-10 inclusive. This modification is similar to the embodiment illustrated in Figs.

1-5 inclusive, except in the following particulars: The member 54, corresponding to the member 19 of the first embodiment, is likewise secured to the upper surface of the tie plate. It has a vertical wall 55 against which the edge of the rail abuts. It is not, however, provided with lateral side wings, but is "off"-rectangular in shape with its end and forward walls being rounded off towards its upper surface. Moreover, as shown, provision is here made for two securing bolts 56 and 57, each of which is adapted to be inserted in cut-outs, 58 and 59, similar to the cut-outs 25 and 28 in the first embodiment. It will be noted that the brace member (Fig. 5) is provided with two holes 39 and 41 (besides the central hole 40) to accommodate the two securing bolts 56, 57 when such brace member is used with the embodiment of Figs. 8-10.

The embodiment of Figs. 8-10 inclusive also differs in that the wedge 60 has a raised upper surface 61 provided with a series of holes 62. Instead of the plate 47 used in the first embodiment, the modification of Figs. 8-10 makes use of a plate 63 which has a portion adapted to extend over the wedge. The overlapping portion is provided with holes 64 which are adapted to align with the holes 62 in the wedge 60 so that a cotter pin 65 can be passed through aligned holes in the plate 63 and in the wedge 60 so as to lock the wedge in place.

Finally, instead of employing members such as the member 19 of Figs. 1-5, and the member 54 of Figs. 8-10, the bolt may be passed through a hole in the tie-plate from below. This, as will be apparent, is subject to disadvantages which to some extent may be overcome by employing the arrangement illustrated in Figs. 11 and 12. In these figures it will be noted that the tie plate 66 is provided with a hole 67 which in diameter is slightly larger than the diameter of the head of a round bevel headed bolt 68. Communicating with the hole 67 is a slot 69 the lower portion of which is beveled, while the upper portion of which is just wide enough to receive the shank of the bolt 68. It will be apparent that with such an arrangement it will be possible to insert the bolt from above by dropping it in the hole 67 and then sliding it in the slot 69 in a direction toward the rail. In the position shown in Figs. 11 and 12, the bolt is held securely in place since the head is disposed beneath the beveled portion of the slot 69.

The various forms of the invention illustrated and described herein are by way of example and it should be obvious that some changes may be made in the shape and relationship of the parts without departing from the invention. The invention therefore is not to be limited except as indicated by the scope of the claims which follow.

I claim:

1. A rail brace comprising, a base plate, the upper surface of which is provided with first and second abutments spaced from each other and adapted when in operative position to be disposed on opposite sides of a rail with the first abutment engaging one edge of the rail base, and the other being spaced from the opposite edge of the rail, a brace member having a portion adapted to be positioned on said base plate, a top portion extending to a point beneath the head of the rail, and depending side walls the lower edges of which engage the upper surface of the base of the rail, said portion adapted to be positioned on said base plate having a side surface facing said second abutment, the facing

surfaces of said brace member and said second abutment being contained in non-parallel vertical planes, a wedge having side surfaces complementary to said facing surfaces of said brace member and said second abutment, a tongue-and-groove connection between said wedge and said second abutment, said groove having a vertical distance greater than said tongue, and facing surfaces of said wedge and said brace member forming a cylinder and socket joint when the wedge is driven in place in a longitudinal direction between said brace member and said second abutment, and a positioning member rigid with the base plate and extending upwardly from the upper surface thereof, and having a vertical wall adjacent and parallel to the edge of the base of the rail and surfaces for engaging the depending side walls of said brace member when the latter is disposed thereover in bracing position, whereby the brace member is prevented from movement longitudinally of the rail, said positioning member having at least one cut-out to receive the square head and shank of a securing bolt to anchor the same, said brace member having at least one hole therein through which the securing bolt may be passed, if desired, so that the brace member may be bolted with respect to the base plate, the portion of said cut-out adapted to receive the square head of the securing bolt being square with its entrant walls at an acute angle from a line perpendicular to the edge of the rail.

2. A rail brace comprising, a base plate, the upper surface of which is provided with first and second abutments spaced from each other and adapted when in operative position to be disposed on opposite sides of a rail with the first abutment engaging one edge of the rail base, and the other being spaced from the opposite edge of the rail, a brace member having a portion adapted to be positioned on said base plate, a top portion extending to a point beneath the head of the rail, and depending side walls the lower edges of which engage the upper surface of the base of the rail, said portion adapted to be positioned on said base plate having a side surface facing said second abutment, the facing surfaces of said brace member and said second abutment being contained in non-parallel vertical planes, a wedge having side surfaces complementary to said facing surfaces of said brace member and said second abutment, a tongue-and-groove connection between said wedge and said second abutment, said groove having a vertical distance greater than said tongue, and facing surfaces of said wedge and said brace member forming a cylinder and socket joint when the wedge is driven in place in a longitudinal direction between said brace member and said second abutment, and a positioning member rigid with the base plate and extending upwardly from the upper surface thereof, and having a vertical wall adjacent and parallel to the edge of the base of the rail, and surfaces for engaging the depending side walls of said brace member when the latter is disposed thereover in bracing position, whereby the brace member is prevented from movement longitudinally of the rail, said positioning member having at least one cut-out to receive the square head and shank of a securing bolt to anchor the same, said brace member having at least one hole therein through which the securing bolt may be passed, if desired, so that the brace member may be bolted

with respect to the base plate, the portion of said cut-out adapted to receive the square head of the securing bolt being square with its entrant walls at an acute angle from a line perpendicular to the edge of the rail, said positioning member having an opening communicating with said cut-out and extending through the base of said vertical wall of said positioning member.
